**TRIGGERED THYRATRON PULSE DISTRIBUTOR
WITH STANDBY TUBE**

Hans H. Adelaar and Jean L. Masure, Antwerp, Belgium, assignors to International Standard Electric Corporation, New York, N.Y., a corporation of Delaware

Filed Sept. 8, 1958, Ser. No. 759,564

Claims priority, application Netherlands Sept. 17, 1957
4 Claims. (Cl. 315—84.5)

The invention relates to a triggered pulse distributor, and more particularly to a pulse distributor for the production of phase shifted trains of pulses of equal frequency, each stage of said distributor being triggered to deliver an output pulse upon the joint occurrence of a trigger pulse, an enabling pulse and a delayed output pulse from the stage of the distributor which was previously triggered.

If such a pulse distributor operating on a ring counter basis must be designed to deliver phase shifted trains of pulses of appreciable power, for instance when it is to be used to produce pulses for the control of telephone exchanges, it may be attractive to use power gas tubes as the active elements for the distributor stages. However, such power gas tubes if they are to be exploited at their maximum power rating, must be capable of handling pulses of large amplitudes, e.g. 600 volts, and such voltage levels are generally not suited to the purpose in view, since the power should generally be delivered at a much lower voltage level, e.g. 20 volts or so.

The object of the invention is to design pulse distributors using gas tubes and adapted to handle large amounts of power.

In accordance with a characteristic of the invention, a triggered pulse distributor of the type defined above is characterised in that each stage includes at least one power gas tube, e.g. a thyatron, working substantially at its maximum rated voltage, that said enabling pulses are applied to the anodes of said gas tubes to enable them to be fired upon the joint occurrence of said trigger pulse, derived from said enabling pulse, and of said delayed output pulse so that said trigger pulse reaches and fires the auxiliary gap of a particular gas tube, and that step-down output transformers are connected to the cathodes of said gas tubes to reduce the pulse voltages obtained at the cathodes when the corresponding gas tubes are fired.

In this manner, the primary winding of the output transformer need not follow the steep output waveforms of the pulses applied to the anode of the power gas tube. This means that the power output transformer which has necessarily an appreciable capacitance with respect to ground, will not constitute an undesirable load for the anode pulse source, since it will be decoupled from the latter by way of the power gas tube.

In accordance with another characteristic of the invention, a triggered pulse distributor as previously defined, is characterised in that the cathode of said gas tube is connected to a first fixed D.C. potential through a first rectifier and that the end of the primary winding of said transformer which is not directly connected to said cathode is connected to a second fixed D.C. potential through a D.C. bias source calculated to minimize the magnetizing current of said transformer while it allows said first rectifier to clamp said cathode to said first D.C. potential in the intervals between cathode pulses without creating a D.C. voltage component across said transformer and that said cathode is coupled to the grid circuit of said gas tube through a first D.C. restorer, whereby a floating but constant negative D.C. bias is provided between said grid and said cathode and the grid limiting resistance may be of low value.

2

FIG. 1 is a composite schematic wiring and block diagram of a multi-stage pulse distributor according to the invention;

FIGS. 2, 3, 4 and 5 are respective wave diagrams used in explaining the operation of the system of FIG. 1.

It will therefore be appreciated that the use of a cathode output transformer for the purpose envisaged is even more advantageous when a D.C. bias source is used to polarise the primary winding of the output transformer so that the cathode end thereof may be clamped to a fixed D.C. potential without creating a D.C. voltage component across the transformer. The main advantage of this clamping arrangement is that the cathode of the gas tube is not allowed to go negative after each conduction interval, which would endanger the required de-ionization of the gas tube. With such an output cathode transformer, the required D.C. bias may have one of its ends connected to a fixed D.C. supply source whereby it can be used in common for all the output transformers in the various stages of the distributor. This will be particularly advantageous when the D.C. bias source is an automatic bias arrangement since the by-pass condenser may then be made very small.

Further, the floating D.C. bias between the cathode and the grid of the gas tube will avoid a substantial potential difference between the cathode and grid when the potential of the former is raised upon an output pulse being produced. Otherwise, one would have to provide a large grid limiting resistor to limit grid current and this would be undesirable as it would increase the de-ionization time of the gas tube. Moreover, it would also delay the ionization time of the auxiliary gap.

The above and other objects and characteristics of the invention will be better understood from the following description of a detailed embodiment thereof, to be read in conjunction with the accompanying drawing which represents one stage of a triggered pulse distributor in accordance with the invention.

Referring to FIG. 1 there are shown a number of stages designated stage No. 1, stage No. 2, and the final stage, stage "n," one particular stage ST (stage No. 2) of a pulse distributor comprising n such stages connected in well known ring counter fashion. Each stage comprises a thyatron TH of which the anode is connected to terminal P_6 through a key K. At terminal P_6 a square waveform is shown, which may have for example a frequency of 2 kc./s., and the voltage of which may swing between -130 volts and 390 volts. The cathode of thyatron TH, to which the second grid is connected, is biased to -130 volts through the primary winding of the cathode output transformer T_1 in series with the automatic bias network R_4/C_4 which, as shown by the multiplying arrow is used in common for all the n stages of the distributor. The control grid of thyatron TH is biased to -200 volts through the grid limiting resistor R_7 in series with resistors R_8 and R_9 . Resistor R_8 is a load resistor for the secondary winding of the input transformer T_2 across the primary winding of which will be applied trigger pulses to cause the ionization of the thyatron. One secondary winding of the cathode output transformer T_1 has been shown and one of its ends is directly connected to -90 volts while the other end is connected to output terminal P_3 through a rectifier W_6 . It is also connected to terminal P_2 which leads to the input terminal of the next stage. The input terminal for stage ST which is shown, and coming from the preceding stage, is P_1 and when a suitable positive pulse arises thereat, it will be applied through resistor R_1 in series with a saturable reactor SR. The end of SR on the other side of resistor R_1 is shown to be grounded through condenser C_1 . The arrangement of R_1 , SR and C_1 constitutes a ferro-resonant circuit which may be

suitably designed to produce a pulse across condenser C_1 which is a replica of the input pulse to terminal P_1 but which is delayed by a certain time which will be assumed to be equal for example to 125 microseconds. More details concerning this arrangement may be obtained from our copending U.S. patent application Serial No. 708,253, filed January 10, 1958, and entitled "Pulse Delay Circuit."

As shown on the drawing, negative trigger pulses are regularly applied at terminal P_4 which is capacitively coupled through condenser C_2 to the lower end of the primary winding of the input transformer T_2 of which the upper end is connected to the floating end of condenser C_1 through rectifier W_1 .

The lower end of the primary winding of transformer T_2 is biased to -90 volts through resistor R_2 in series with resistor R_5 , the former being shunted by rectifier W_2 and the latter by smoothing condenser C_5 . It will be recognized that condenser C_2 , rectifier W_2 and resistor R_2 constitute a D.C. restorer for coupling the negative trigger pulses at terminal P_4 to the primary winding of transformer T_2 . On the other hand, resistor R_5 shunted by condenser C_5 constitutes an automatic bias network which rectifies the pulses appearing at the various output terminals such as P_2 all of which are connected to this automatic bias network through an individual rectifier W_5 so that during the operation of the pulse distributor, a potential difference of some 90 volts will appear across resistor R_5 raising the bias of the D.C. restorer to about ground potential. Such an automatic bias network is only provided for the first stage of the distributor which will be the first to be triggered when starting the operations. For the remaining stages of the distributor, the cathodes of the rectifiers such as W_2 are directly biased to ground potential. This automatic bias network R_5/C_5 will permit to bring the anode of rectifier W_2 to a potential which is under the bias potential of -90 volts by an amount corresponding to the amplitude of the negative trigger pulse e.g. 100 volts, when the latter arises. The instantaneous negative potential thus produced at the lower end of the primary winding of transformer T_2 will be sufficiently lower than the potential of -90 volts initially prevailing at the floating end of condenser C_1 , to initially render rectifier W_1 conductive though no output pulse from the previous stage can yet be applied at terminal P_1 . More details concerning these particular starting circuits are shown in U.S. Patent No. 2,928,939, issued March 15, 1960.

As a result of rectifier W_1 being made conductive, a current pulse will flow through the primary winding of transformer T_2 and will induce a voltage, e.g. 100 volts, across the secondary winding of this transformer which will have sufficient amplitude to overcome the negative bias which the control grid of thyatron TH possesses with respect to its cathode, i.e. $-200 - (-130) = -70$ volts. Accordingly, thyatron TH will fire and will produce a positive output pulse at its cathode which will be reproduced across the secondary winding biased to -90 volts to reach the output terminals P_2 and P_3 .

It will be noted that the cathode of thyatron TH is coupled to the lower end of resistor R_8 through condenser C_3 and that resistor R_3 is shunted by rectifier W_3 . These last three elements also constitute a D.C. restorer which permits to keep a constant floating bias between the cathode of the thyatron and its grid circuit. Otherwise, if the control grid were not positively tied to the cathode in this manner, resistor R_7 would have a much larger value in view of the high voltage pulses appearing at the cathode of the thyatron. This would substantially hinder the de-ionization as well as the ionization of the thyatron. With a mere capacitive coupling between the cathode and the grid of the thyatron, the voltage capacitively coupled into the grid circuit would be subjected to exponential variations unless the time constant is very large. Moreover, the grid bias of -200

volts would have to be raised to take into account the fact that the potential at the left-hand side of condenser C_3 would go below the fixed bias level by an amount equal to aE where a is the time duty ratio of the pulses at the cathode and E their amplitude. Variations of aE would therefore also cause variations in the floating D.C. bias between cathode and grid. When the rectifier W_2 is added to prevent negative voltage excursions below -200 volts, between successive pulses, the cathode will be at -130 volts while the grid will be biased to -200 volts to maintain the desired bias of -70 volts. During the pulses, the full amplitude of the voltage step of +520 volts (abstraction being made of the small plate-to-cathode potential) at the cathode of the thyatron will be injected into the grid circuit to raise the absolute value of the bias of the grid but maintaining its relative value with respect to the cathode potential, at -70 volts below the latter, i.e. $+390 - 70 = 320$ volts.

Between the pulses, the cathode of the thyatron is at -130 volts because it is clamped to that potential through rectifier W_4 in series with the winding of the common relay Tr used for all the n stages of the distributor. Across resistor R_4 , a potential of aE volts is developed to avoid that a D.C. voltage component should arise across the primary winding of transformer T_1 which would tend to saturate the latter. At the same time, this automatic bias across resistor R_4 still permits rectifier W_4 , which is blocked during a positive pulse at the cathode, to be conductive between successive pulses. Additional information concerning this particular output transformer circuit may be found in Belgian Patent No. 571,265, issued March 17, 1958. Relay Tr will regularly receive current during the intervals between successive pulses and may therefore be arranged to normally remain operated. If it should release, this may therefore be used to give an indication that the rectifiers such as W_4 no longer conduct between pulses, which might for example arise if the voltage across R_4 becomes larger than the value of aE . Then, the value of R_4 could be adjusted to decrease the voltage across this resistance to the optimum value.

During the operation of the pulse distributor, the first stage shown will function in the same way as the other stages, i.e. an output pulse from the previous stage and appearing at terminal P_1 will be necessary to produce a delayed pulse raising the anode voltage of rectifier W_1 . In such a case, although the negative trigger pulse capacitively fed from P_4 will be based on a level substantially equal to ground by virtue of the clamping action of rectifier W_2 and the potential difference of about 90 volts across R_5 , the potential difference across rectifier W_1 will be sufficient to unblock it and induce a positive trigger pulse into the grid circuit of the thyatron to ionize the latter. Deenergisation of the thyatron TH will of course occur upon the disappearance of the anode pulse at terminal P_6 .

The use of the D.C. restorer C_2 , R_2 , W_2 for injecting the trigger pulses permits to base these on a fixed D.C. level which will be found useful in connection with the gating rectifier W_1 . The input transformer T_2 is a convenient way to isolate the two D.C. restorers.

Whenever an absolute reliability of operation is required, for example for use in telephone exchanges, failure of a thyatron should not cause a failure of the distributor. In the Belgian Patent No. 523,622 (C. Weill et al., December 9, 1918), it has already been proposed to associate a spare thyatron with a normally working thyatron, the latter being normally given preference in operation due to a lower bias. Since the pulses used to fire the thyatrons must necessarily have a finite slope, the thyatron with the small bias will be the first to ionize. As soon as it is ionized, use of a common load impedance will readily prevent the ionization of the spare

thyatron which will only fire if the normal tube fails to do so.

Such an arrangement is however quite awkward to apply to the circuit shown since one would have to go to the expense of duplicating the floating biasses arrangements. Instead, the figure shows that the spare thyatron TH' which has its cathode and its second grid commoned to those of thyatron TH, while its anode is commoned to that of TH through the primary winding of transformer T₃, has its control grid connected to the control grid of TH through a simple delay circuit comprising resistor R₆ between the two control grids and shunt condenser C₆ between the control grid and the cathode of TH'. In this manner, the two thyatrons may be biassed by a common arrangement and thyatron TH' will normally never fire since thyatron TH is given preference. Moreover, one is no longer dependent on the shape of the pulses applied to the control grid of the normal thyatron TH. Should thyatron TH fail to be ionized within the time delay provided by R₆/C₆, TH' will fire instead. This delay produced by R₆/C₆ will of course be chosen quite small with respect to the duration of the output pulses so that if the spare thyatron comes into action, the length of the output pulses will hardly be reduced.

Transformer T₃ will permit to induce a voltage between terminal P₅ and P'₅ upon the firing of TH'. A non-urgent alarm can therefore be given to the maintenance staff. Preferably, terminals P₅ and P'₅ will be connected to a relay detecting arrangement through a rectifier network (not shown) so that it is only the repeated firing of the spare thyatron TH' which will be detected, and odd and temporary failures of TH to fire first remaining unnoticed. If TH fails key contact K may disconnect it from the circuit.

The waveforms shown indicate that the trigger pulses at terminal P₄ lag by 1/4 of a period behind the positive flanks of the anode pulses at P₆. Therefore, the ferro-resonant delay device may conveniently be arranged to produce a delay of 1/2 a period. The delay from one stage to the next should obviously be larger than the delay of the trigger pulses, since otherwise the delayed pulse would end before the occurrence of the trigger pulse. On the other hand, with the ferro-resonant delay circuit, the delayed input pulse cannot start after the output pulse from the previous stage has subsided. Therefore, the limits are in the present case: 1/4 of a period and 3/4 of a period which limits justify the value shown on the figure.

It will be remarked that the gating arrangement for the trigger pulses includes the rectifier W₁ whereby, since the load at terminal P₃ is also connected through a rectifier W₆ and since a rectifier W₅ is also used to produce the automatic starting bias, the load seen at the cathode of the thyatrons is unidirectional, being chosen, to be quite high in the intervals between the pulses and thereby limiting the value of the magnetising current through the transformer.

While the principles of the invention have been described above in connection with specific apparatus, it is to be clearly understood that this description is made only by way of example and not as a limitation on the scope of the invention.

What we claim is:

1. A multi-stage triggered pulse distributor for generating phase-shifted trains of pulses of equal frequency,

comprising means for connecting each stage to a source of triggering pulses, to a source of enabling pulses, and to delayed pulses from an immediately preceding stage, a power gas tube in each stage having an anode, a control electrode, and a cathode, means for applying the said enabling pulses to the said anode of any said tube simultaneously with the joint application of triggering pulses and delayed pulses to the said control electrode thereof to ionize the last said tube to generate a voltage output pulse, each of said tubes having an output transformer and first and second clamping means associated therewith, a primary winding on each said output transformer, means for connecting each said primary winding between the said cathode of its associated tube and a first direct current potential, means for connecting each said first clamping means between the said cathode of its associated tube and the said first direct current potential, to clamp said cathode to said first potential, and means for connecting each said second clamping means between the control electrode of its associated tube and a second direct current potential to reduce the pulse voltage obtained at the cathode when the associated tube is fired and to provide a constant negative direct current bias between the said control electrode and said cathode of said associated tube.

2. A multi-stage triggered pulse distributor as claimed in claim 1, wherein each said second clamping means includes a rectifier in circuit with the said control electrode of its associated tube and includes a first direct-current restorer between said control electrode and said cathode of its associated tube.

3. In a multi-stage triggered pulse distributor as claimed in claim 2, each of said tubes having an input transformer associated therewith, each said input transformer having a primary and a secondary winding thereon, the said means for applying said delayed pulses to said control electrode of any tube including a second rectifier connected to one end of the said primary winding of the associated input transformer, the said means for applying said triggering pulses to said control electrode of the last said tube including a second direct-current restorer connected to the other end of the primary winding of the last said input transformer, and means connecting the secondary winding of the last said input transformer between the said control electrode of the associated tube and the associated first clamping means to change the conductivity of the last said rectifier to generate a pulse across the secondary of the associated input transformer.

4. In a multi-stage triggered pulse distributor as set forth in claim 1, each of said gas tubes having a second gas tube associated therewith with each second gas tube including an anode, a control electrode and a cathode, means for connecting the said anodes and said cathodes of the second tubes to respective anodes and cathodes of their said associated tubes, delay means for each stage including a resistor and a condenser, means including the said delay means for connecting the said control electrode of each second gas tube to the control electrode of its associated gas tube, whereby the said second gas tube of any stage is permitted to ionize only upon failure of the associated tube to ionize.
